PIPE WRENCH HAVING A PIVOTABLE AND LONGITUDINALLY MOVABLE INNER JAW

Elmer Nickerson, Outlook, Mont., assignor to
Lorna E. Harris, Concord, Calif.

Application November 14, 1951, Serial No. 256,182

6 Claims. (Cl. 81—92)

The invention relates to a wrench for gripping work-pieces comprising pipes or other cylindrical members.

A primary object is to provide a wrench of the character described by which a particularly rapid gripping and release of a workpiece may be effected.

Another object is to provide a wrench in which the securing means for the movable jaw thereof is fully protected within a stock member which unitarily provides the fixed jaw.

The invention possesses other objects and features of advantage, some of which, with the foregoing, will be set forth or be apparent in the following description of a typical embodiment of the wrench, and in the accompanying drawings, in which,

Figure 1 is a perspective view of a wrench embodying the features of my invention.

Figure 2 is an enlarged side view of the head portion of the wrench having the near side plate of the head removed for showing the mounting and control means for the movable jaw in normal relation.

Figure 3 is a view of the parts shown in Figure 2, but with the movable parts disposed for a shifting of the movable jaw toward or away from the fixed jaw.

Figure 4 is a transverse section taken at the broken line 4—4 in Figure 3.

Figure 5 shows the relation of the wrench head parts after the wrench has released its grip on a cylindrical work-piece and preparatory to swinging the wrench handle to obtain a fresh grip.

The features of my invention are particularly disclosed as embodied in the structure of a wrench 8 comprising a stock 9 providing head and handle portions 11 and 12 respectively. A fixed jaw 13 extends obliquely forwardly and laterally from the free end of the head portion 11 in the plane thereof, and said head portion provides a recess 14 opening at the front of the stock and extending rearwardly from the jaw 13. The recess 14 guidedly receives hingedly articulated and mutually coplanar jaw and catch plate members 15 and 16 for their adjusted disposal along the recess, with the jaw member 15 providing a forward jaw portion 17 extending laterally from the recess 14 and having a working edge face 17' in cooperative opposition to a working edge face 13' of the fixed jaw 13.

A pivot pin 18 extends transversely through a circular bearing bore in the catch member 16 and has end portions slidably engaged in mutually coplanar slots 19 provided in the sides of the recess 14 and extending longitudinally of the head to provide for independent rocking and sliding adjustments of the catch member 16. In the present wrench structure, the pivot pin 18 has a flattened side 18' extending from a full-circle head portion 18" and engaging corresponding sides of the slots 19 for holding the pin against its rotation in the slots, whereby the member 16 is rockable about the mounted pin. The pin 18 may be removably retained in its mounted position by means of a C-ring 20 gripping the unheaded extending pin end at an encircling groove provided thereat, the pinhead 18" and

the ring 20 engaging the outer faces of the members which define the recess, for retaining the pin in its place.

Referring now to the specific structure of the present stock 9, it will be noted that this unitary element of the wrench is provided as a fabricated structure by fixing a pair of complementary cheek-plate members 21 and 22 to members 23 and 24 of like and uniform thickness which cooperate as spacers at the head and handle portions of the stock between the members 21 and 22 which thus provide the outer side faces for the wrench. The various exposed outer edge portions of the member 23 are flush with the corresponding edge portions of the side plates 21 and 22, it being noted that the jaw 13 comprises an integral angular extension of the relatively narrow member 23 and extends appreciably in front of the intersected common plane of the adjacent front edge portions 25 of the plates 21 and 22. Straight front edge portions 26 of the side plates 21 and 22 are offset with respect to the edges 25 of said plates in a plane which is parallel to the plane of the former, and are connected to the latter edges by oblique edge portions 27, it being noted that the free end of the jaw 13 is disposed adjacent the plane of the edges 26 and that the jaw defines the forward end of the channel recess 14.

With reference to the relation of the member 23 to the handle portion of the stock assembly, it will be noted that a straight rear front edge portion 28 thereof abuts a rear outer edge portion 29 of the member 24 between the side plates 21 and 22, and that the side edge of the member 24 otherwise extends slightly beyond the adjacent edge portions of the plates 21 and 22 to provide, in effect, a rounded edge for the handle portion thereof. Adjacent the rear end thereof, the members 21 and 22 and 24 are provided with registering holes which receive a tubular rivet 31 to unitarily secure the members together thereat while providing a hang-up eye for the wrench. Registering holes through the side plates 21 and 22 and the members 23 and 24 receive solid rivets 32 for fixing these elements together to provide the unitary stock structure, it being understood that the present arrangement permits the use of steel cheek-plates to provide a maximum strength and rigidity with a minimum weight of material and a uniform and minimum thickness for the wrench. Since the member 24 of the handle portion serves primarily as a spacer for the handle portions of the side plates 21 and 22, this member may be non-metallic. Also, longitudinal slots 33 may be cut in the handle portions of the side plates 21 and 22 to lighten the structure thereat while exposing face portions of the member 24 to view through the openings; said visible and generally protected side face portions of the member 24 may present size and trademark and patent-status indications, as desired.

It will now be noted that the front edge of the member 23 has, in order, a succession of straight mutually connected portions 34 and 35 and 36 connecting the rearward end of the jaw face 13' and the forward end of the rearward front edge portion 28 of the member, said edge portions all being perpendicular to the plane of the wrench. The edge portion 34 is straight and smooth, while the edge portion 36 is provided with a straight line of dogging teeth 37 extending forwardly of the handle member 24 which is coplanar therewith, and the edge portion 35 connects the portions 34 and 36 which are parallel and mutually offset. A straight back edge portion 38 of the catch member 16 which is disposed opposite the dogging teeth 37 and extends rearwardly of the pivot pin 18 is provided with a line of complementary dogging teeth 39 for holding engagement with the dogging teeth 37 after the member 16 has been adjustably set along the head for a desired adjusted disposition of the hinging axis provided by the pivot pin 18.

As particularly shown, a generally V-shaped notch 41 having front and rear edges 41' and 41" extends into the member 16 from the forward edge thereof, and is provided at its inner end with a cylindrical socket 42 for rotatively receiving a complementary head 43 provided at the extremity of a rearwardly-extending stem portion 44 of the member 15 which provides the jaw 17, the connection comprising a knuckle joint. A trigger arm portion 45 of the member 16 extends forwardly of the pivot pin 18 at the opposite side of the socket from the pin to provide the front side 41' of the notch 41 which terminates in the socket 42, and which is engaged by the confronting edge portion 45' of the member 15 for limiting the swinging of the jaw member 15 away from the stock.

A spring means is constantly coactive between the members 15 and 16 to urge a backward swinging of the member 15 about the knuckle joint 42—43, and such a swinging of the member 16 about the pivot pin 18 as to normally engage the dogging teeth of the latter member with the opposed dogging teeth 37 of the stock member 23 to retain the member 16 against movement along the stock. As particularly shown, the aforesaid means comprises a helical tension spring 46 which extends forwardly from an anchorage point 47 of the member 16 to a connection with an arm 48 which is hinged to the member 15 for a limited rocking thereof with respect to the member. The present arm member 48 comprises a metallic strip bent upon itself to intermediately provide a shoe 49 for slidably engaging the front edge face 34 of the stock element 23, the different end portions of the strip respectively providing a stem portion 51 which is hingedly engaged with the member 15 and an ear portion 52 which provides an anchorage point 53 for the forward end of the spring 46. At its free end, the stem portion 51 of the arm 48 is provided with a cylindrical hinge knuckle 54 which is engaged in a cylindrical socket 55 formed at the inner end of a notch 56 extending into the member 15 from an intermediate point of its back edge.

A limited rocking movement of the arm 48 in the plane of the member 15 and about the axis of the knuckle joint 54—55 is permitted, such movement being limited by the alternative engagement of the stem with stops 57 and 58 comprising the lips of the notch 56. In the present structure, the arm 48 curves forwardly to the shoe 49, and the front arm and shoe faces are normally spaced from the opposed edge face of the member 15 which is generally complementary to the opposed arm face. The normal effective action of the spring 46 is such that the bearing face of the shoe 49 is retained in engagement with the stock face 34, the stem 51 engages the rearward stop 58, the member 15 is slightly spaced from the shoe, and the dogging teeth 37 of the stock are resiliently engaged by the dogging teeth 39 of the catch plate 16, the normal relation of the parts being particularly illustrated in Figure 2 of the drawings.

The present dogging teeth 37 and 39 are shaped as isosceles triangles with respect to their base lines, whereby, under normal conditions, the catch plate 16 and the attached jaw member 15 may be moved either forwardly or rearwardly along the stock against a relatively light frictional wedging coaction of the dogging teeth 39 with the stock teeth to frictionally hold the jaw in set position with a ratchet action which is primarily utilized during a forward work-engaging movement of the jaw 17.

For gripping and turning a cylindrical workpiece W, which might comprise the pipe or tubular rod indicated in Figure 5, the movable jaw 17 is appropriately spaced from the fixed jaw 13 for the disposal of the jaws at opposite sides of the workpiece while the catch plate teeth 39 are disengaged from the stock teeth 37 by reason of the rocking of the catch plate caused in turn by an operator grasping the wrench head and squeezing the trigger arm 45 of the catch plate to the position shown in Figure 3. With a workpiece disposed between the working faces of the jaws and with the catch plate 16 free for rocking about

the pin 18, the jaw 17 is manually and forcibly advanced against the workpiece to rock the jaw plate 15 outwardly to, or approximately to, the limit permitted by the arm 45 of the catch plate 16 after the ratchet engagement of the plate 16 with the stock.

A turning of the installed wrench about a gripped workpiece in an appropriate direction, which is clockwise in either Figure 2 or Figure 5, will rock the jaw 17 toward the stock face 34 and effect a cooperative jamming grip of the workpiece between the jaws while positively anchoring the plate 16 to the stock by the coaction of the dogging teeth; it will be understood that said actions are due to the fact that the rearward swinging of the jaw face 17' moves the latter toward the fixed jaw face 13'.

15 while the work-gripping reaction of the jaw plate 15 rocks the catch plate 16 to effect a positive interlocked engagement of the catch plate teeth 39 with the stock teeth 37. It will also be understood that a reverse rotation of the wrench about a gripped cylindrical workpiece will move the jaw plate 15 from its Figure 2 to its Figure 5 position so as to permit a ratcheting action with respect to the workpiece.

20 While the present wrench has the working face of its fixed jaw oblique to the longitudinal stock axis, it will be understood that the jaw angle might be varied or be made ninety degrees, provided only that the gripping face 17' of the movable jaw 17 extends forwardly from a line perpendicular to it and extending through the axis of the knuckle joint provided by the head 43 and socket 42 of the plates 25 15 and 16 respectively. It is also to be noted that the various metallic plate elements of the wrench may comprise sheet steel stampings in a particularly strong and rigid structure which is relatively thin for its possible working application in narrow spaces.

25 30 35 From the foregoing description taken in connection with the accompanying drawings, the advantages of the present wrench will be readily understood by those skilled in the art to which the invention appertains. While I have described the structure and use of a form of my invention which I now consider to comprise a preferred embodiment thereof, I desire to have it understood that the disclosure is primarily illustrative, and that such changes and developments may be made, when desired, as fall within the scope of the following claims.

40 I claim:

45 50 55 60 65 1. In a pipe wrench, an elongated stock providing a jaw extending fixedly from the front side thereof and having a working edge portion directed transversely of said stock side, said stock having a line of dogging elements provided along said side thereof, a movable jaw comprising a plate member having a working edge portion for work-gripping coaction with the working edge of said fixed jaw, a catch plate hingedly connected to the movable jaw plate to extend rearwardly thereof, said catch plate having dogging elements along a back edge portion thereof for cooperatively engaging the dogging elements of the stock, spaced cheek-plate member portions of the stock extending beyond said front side having the dogging elements and cooperative to guidedly and retainedly receive the jaw plate and catch plate between them, and means pivotally mounting the catch member directly on the cheek-plates for its rocking between positions in which its dogging teeth are operative or inoperative with respect to the dogging elements of the stock and for its sliding adjustment along the stock when the dogging elements are inoperative.

70 75 80 85 90 2. A structure in accordance with claim 1 wherein the last means comprises a pivot pin engaged through the catch plate and having its ends slidably engaged in mutually parallel guide slots provided in the cheek-plates.

3. In a pipe wrench, an elongated stock providing a fixed jaw extending from its front side at its forward end and having dogging teeth provided along a portion of said side rearwardly of the jaw, a catch member extending in front of the stock and provided with dogging teeth

normally engaging the teeth of the stock, a pivot means mounting the catch member on the stock for adjustments of its pivot axis along a line longitudinal of the stock and for its independent and manual rocking to disengage its teeth from the stock teeth, a movable jaw member carried by the catch member and hingedly connected thereto at a point thereof in front of the line of adjustment of the pivot means and extending forwardly of said point to present its working face opposite the working face of the fixed jaw, a yielding means normally cooperative between the movable jaw member and the stock and the catch member to dispose the working face of the movable jaw member in a position from which it is swung outwardly with respect to the stock by reason of its cooperation with the fixed jaw to release its grip on a workpiece while the dogging teeth of the catch member are maintained in interlocked engagement with the locking teeth of the stock and a trigger arm extending forwardly from the catch member opposite and outwardly of the movable jaw for manual engagement to rock the catch member for freeing its teeth from the teeth of the stock.

4. In a pipe wrench, an elongated stock providing a fixed jaw extending from its front side at its forward end and having dogging teeth provided along a portion of said side rearwardly of the jaw, a catch member extending in front of the stock and provided with dogging teeth normally engaging the teeth of the stock, a pivot means mounting the catch member on the stock for adjustments of its pivot axis along a line longitudinal of the stock and for its independent and manual rocking to disengage its teeth from the stock teeth, a movable jaw member carried by the catch member and pivotally connected thereto at a point thereof in front of the line of adjustment of the pivot means and extending forwardly of said point to present its working face opposite the working face of the fixed jaw, and a tension spring directly operative between the catch member and the movable jaw member and in a line between the pivot points of the pivoted members and the confronting edge of the stock, said tension spring being normally cooperative with the movable jaw member and the stock and the catch member to dispose the working face of the movable jaw member in a position from which it is swung outwardly with respect to the stock by reason of its cooperation with the fixed jaw to release its grip on a workpiece while the dogging teeth of the catch member are maintained in interlocked engagement with the locking teeth of the stock.

5. In a pipe wrench, an elongated stock providing a fixed jaw extending from its front side at its forward end and having dogging teeth provided along a portion of said side rearwardly of the jaw, a catch member extending in front of the stock and provided with dogging teeth normally engaging the teeth of the stock, a pivot means mounting the catch member on the stock for adjustments

of its pivot axis along a line longitudinal of the stock and for its independent and manual rocking to disengage its teeth from the stock teeth, a movable jaw member carried by the catch member and hingedly connected thereto at a point thereof in front of the line of adjustment of the pivot means and extending forwardly of said point to present its working face opposite the working face of the fixed jaw, a strut arm having one end hingedly engaged with the movable jaw and normally having its other end in slidable engagement with an untoothed portion of the front stock side forwardly of its toothed portion, and a spring operative in tension between an intermediate arm point and the catch member to urge an inward disposal of the jaw member with respect to the stock and the engagement of the catch teeth with the stock teeth.

6. In a pipe wrench of the character described, an elongated stock providing a fixed jaw extending from its front side at an end thereof and having dogging teeth provided along a portion of said front side and having planar cheek plate portions extending beyond said front side portion of the stock to define an outwardly-extending channel of uniform width therealong, a catch member slidably engaged in the channel to extend therefrom for its manual engagement and provided with dogging teeth normally engaging the teeth of the stock, a pivot pin mounted on the cheek plates and having its pivot axis extending transverse to the planes of the cheek plates, means slidably mounting said pivot pin for adjustment of said pivot axis along a line in front of and longitudinal of the stock, said catch member being pivotally mounted on the pivot pin for slidable movement therewith and for an independent rocking movement about said pivot axis, said rocking movement disengaging the teeth of said catch member from the stock teeth, and a movable jaw member disposed in the channel and swingably connected to the catch member at a point thereof in front of the line of adjustment of said pivot pin axis, said movable jaw member being swingable about an axis parallel to said pivot pin axis, and said movable jaw member extending forwardly of the catch member to present its working face opposite the working face of the fixed jaw for a gripping of a workpiece disposed between the jaws by reason of a swinging movement of the movable jaw toward the stock.
